UNITED STATES PATENT OFFICE.

CARL RÖSTEL, OF BERLIN, GERMANY.

FIELD-GUN-CARRIAGE RECOIL-CHECK.

SPECIFICATION forming part of Letters Patent No. 597,126, dated January 11, 1898.

Application filed February 12, 1897. Serial No. 623,161. (No model.) Patented in Germany November 24, 1896, No. 94,012; in England January 11, 1897, No. 732; in France January 11, 1897, No. 262,961, and in Belgium January 11, 1897, No. 125,900.

To all whom it may concern:

Be it known that I, CARL RÖSTEL, engineer, a subject of the King of Prussia, German Emperor, residing at Friedrichstrasse 43, Berlin, 5 in the Kingdom of Prussia and Empire of Germany, have invented certain new and useful Improvements in Recoil-Brakes, (for which I have obtained patents in Germany, No. 94,012, dated November 24, 1896; in England, No. 10 732, dated January 11, 1897; in France, No. 262,961, dated January 11, 1897, and in Belgium, No. 125,900, dated January 11, 1897;) and I do hereby declare the following to be a 15 full, clear, and exact description of the invention, such as will enable others skilled in the art to which it appertains to make and use the same.

This invention relates to a recoil-brake for the gun which constitutes the means for 20 turning the gun after firing to its initial or firing position by causing a piston in the recoil-brake cylinder to force liquid between two spring-actuated disks or plungers in the interior of the hollow axle of the gun-carriage, 25 which latter acts as an accumulator and forces the gun again forward after each recoil. The said cylinder and parts connected thereto also form the gun-carrier.

The invention is illustrated in the accompanying drawings, in which—

Figure 1 is a side elevation, partly in section, of a gun and gun-carriage fitted with my improvements. Fig. 2 is a plan, partly in section, of the recoil mechanism. Fig. 3 35 is a rear view, partly in section, of parts shown in Fig. 1; and Fig. 4 is a sectional view, drawn to a larger scale, of a throttle device which may be used in connection with the present invention for regulating the action of 40 the recoil-brake. Fig. 5 is a sectional plan view of the throttle device.

R is the gun, and B is the axle of the gun-carriage.

D is the gun-carrier, in which the gun slides 45 back and forth longitudinally. The gun-carrier is provided with horizontal pivots a, which are journaled in a bracket a'. The bracket a' is journaled on vertical pivots b, which project from the axle B.

50 The gun and its carrier can be moved rela-

tively to the gun-carriage in a vertical plane about the pivots a as a center and in a horizontal plane about the pivots b as a center.

A is a brake-cylinder secured to the carrier D under the gun and parallel to it.

A' is a piston which is slideable in the cylinder A and which is provided with a piston-rod 3, which is secured to the gun.

An accumulator-cylinder 4 is formed inside the axle B, and B' is a spring-pressed piston 6c which is slideable in the cylinder 4.

C are the springs for moving the piston B' in one direction. The cylinder 4 is preferably provided with two similar spring-pressed pistons, but only one is shown, as the other is 65 an exact duplicate of it in the other half of the cylinder. Passages are arranged to connect the rear end of the brake-cylinder with the water-space of the cylinder 4. These passages c pass through the pivots a and the upper pivot b and are so proportioned at the pivots that the two said cylinders are always in free communication with each other irrespective of the motion at the pivots.

The cylinder 4 is of much larger area than 75 the cylinder A.

When the gun is fired, the recoil forces the piston A' rearwardly, and the water behind it is forced through the passages c into the cylinder 4, where it operates the piston or 80 pistons B' and stores up energy by compressing the springs C. The springs C subsequently expand and drive the water in the cylinder 4 back into the brake-cylinder A, thereby propelling the piston A' forward and 85 returning the gun to its original position.

The gun is preferably so arranged that very little of its weight comes on the rear end portion of the gun-carriage which rests on the ground.

In order to regulate the flow of water through the passages c, the said passages are provided with two spring-actuated valves f, provided with operating-levers f'.

R' is a rail secured to the lower part of the 95 gun. This rail is double-tapered, being broadest at a prearranged point 7 near its rear end and narrowest at its ends. The rail tapers from the point 7 to its ends in any approved manner. The levers f' are pressed 100

- toward the rail by their springs. When the recoil commences, the parts are in the positions indicated by the dotted lines in Fig. 5, and the openings through which water may 5 pass through the valves are very small in area. When the gun has partially recoiled and is moving rearwardly with the greatest velocity, the valves are opened wide by the levers f' , the ends of which are then opposite the point 7. The water-openings through the valves are gradually reduced as the velocity of the gun is reduced during the latter part of the recoil. In this manner the action of the brake is regulated and made constant.
- 15 A screw d is provided for adjusting the sight of the gun in a vertical plane when it turns on its pivots a , and a second screw h is provided for adjusting the sight of the gun in a horizontal plane when it turns on the 20 pivots b . The screw d is pivotally supported in the gun-carriage, and the screws d and h are operated in any approved manner. The screw d is pivoted to a shaft d' by a pin d'' . The shaft d' is arranged substantially parallel with the axis of the gun, and it is longitudinally slidable and free to oscillate on its own axis in a socket s on the cylinder A. A slight oscillatory freedom of motion of the shaft d' is requisite to permit the gun to be 25 sighted in a horizontal direction. The pin d'' is provided with handles d''' for operating the shaft d' and raising or lowering the rear end portion of the gun. When the shaft d' is pulled rearwardly and the handles are let 30 go, the shaft d' drops onto the stop e and the parts assume the positions indicated by dotted lines in Fig. 1, so that access to the breech of the gun can be had.
- I do not limit myself to the use of a single 35 brake-cylinder A in carrying out this invention, as one or more brake-cylinders of any approved construction can be connected to the accumulator-cylinder in the axle. The piston in the brake-cylinder may be of any 40 approved construction, a single piston of simple form being shown in the drawings merely for the purpose of illustrating one form of piston which may be used.
- What I claim is—
- 50 1. In a field-gun carriage, the combination, with a slidable gun, of an axle having an accumulator-cylinder formed inside it and extending under the gun, a recoil-brake cylin-

der operatively connected with the accumulator-cylinder, and a piston slidable in the 55 recoil-brake cylinder and connected to the gun, substantially as set forth.

2. In a field-gun carriage, the combination, with a slidable gun, of an axle having an accumulator-cylinder formed inside it and extending under the gun, a piston slidable in the 60 accumulator-cylinder, springs for moving the said piston in one direction, a recoil-brake cylinder operatively connected with the accumulator-cylinder, and a piston slidable in 65 the recoil-brake cylinder and connected to the gun, substantially as set forth.

3. In a field-gun carriage, the combination, with two cylinders connected by passages and forming portions of a recoil-brake, of a double-tapered rail secured to the gun, and valves arranged in the said passages and provided with operating-levers which bear against the opposite sides of the said rail and are moved simultaneously by it in opposite directions 75 when the gun recoils, so that the passages through the said valves are widest open when the velocity of the gun is greatest, substantially as set forth.

4. In a field-gun carriage, the combination, with a brake-cylinder provided with a piston operatively connected to the gun, of an axle provided with an accumulator-cylinder and vertical pivots, a spring-pressed piston in the accumulator-cylinder, a bracket journaled on 85 the said pivots, and a support for the gun secured to the said brake-cylinder and provided with horizontal pivots journaled in the said bracket, said cylinders being operatively connected by passages which extend through the 90 said pivots, substantially as set forth.

5. In a field-gun carriage, the combination, with a cylinder formed within the axle of the carriage and provided with an inlet-passage at its middle part, of two similar pistons slidable in the said cylinder one on each side of the said passage and forming portions of a recoil-brake, and springs in the opposite ends of the said cylinder pressing the said pistons toward each other, substantially as set forth. 95

In testimony whereof I affix my signature in presence of two witnesses.

CARL RÖSTEL.
